(57) **CLAIM**

The ornamental design for a partially concealed wheel housing, as shown and described.

DESCRIPTION

FIG. 1 is a perspective view of a partially concealed wheel housing showing my new design;
FIG. 2 is a side elevational view thereof;
FIG. 3 is a front elevational view thereof;
FIG. 4 is a rear elevational view thereof;
FIG. 5 is a top view thereof, the bottom view being a mirror image;
FIG. 6 is a perspective view of a second embodiment of my new design;
FIG. 7 is a side elevational view thereof;
FIG. 8 is a front elevational view thereof;
FIG. 9 is a rear elevational view thereof; and,
FIG. 10 is a top view thereof, the bottom view being a mirror image.

The broken line showing of the remainder of the wheel housing is for illustrative purposes only and forms no part of the claimed design.
